US0D1071674S

(12) **United States Design Patent** (10) **Patent No.:** **US D1,071,674 S**
(45) **Date of Patent:** **** Apr. 22, 2025**

(54) **SNACK CONTAINER**

(71) Applicant: **Mengting Xiao**, Shenzhen (CN)

(72) Inventor: **Mengting Xiao**, Shenzhen (CN)

(**) Term: **15 Years**

(21) Appl. No.: **29/949,058**

(22) Filed: **Jun. 25, 2024**

(51) LOC (15) Cl. **09-07**

(52) U.S. Cl.

USPC **D7/629**

(57) **CLAIM**

The ornamental design for a snack container, as shown and described.

DESCRIPTION

FIG. 1 is a perspective view of a snack container showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is the opening state of the snack container thereof; and,

FIG. 9 is an exploded view of the snack container thereof. The broken lines shown in the drawings depict portions of the snack container that form no part of the claimed design.

1 Claim, 9 Drawing Sheets
